SURFACE ORNAMENTATION OF WALLS, &c.

No. 16,239.

Patented Sept. 8, 1885.

UNITED STATES PATENT OFFICE.

FREDERICK MANKEY, OF WILLIAMSPORT, PENNSYLVANIA.

DESIGN FOR SURFACE ORNAMENTATION OF WALLS, &c.

SPECIFICATION forming part of Design No. 16,239, dated September 8, 1885,

Application filed July 18, 1885. Term of patent 7 years.

To all whom it may concern:

Be it known that I, FREDERICK MANKEY, of Williamsport, Lycoming county, Pennsylvania, have invented and produced a new and 5 original Design for Surface Ornamentation of Walls, &c., of which the following is a specification, reference being had to the accompanying photograph, forming part hereof.

My design consists in truncated hexagonal pyramidal elevations A, formed upon the surface and disposed in a row longitudinally the same. Said elevations A alternate with two trilateral pyramidal elevations, B and C. The elevations B and C are placed point to 15 point, as shown, and are separated from the adjacent elevations A by channels D E, formed diagonally across the surface. On the summit of each elevation A is formed a flat-surfaced hexagonal elevation, F. The elevations B and 20 C are separated from the elevations A by

channels or spaces D E, diagonally disposed across the surface, and the longitudinal rows of elevations are separated from each other by longitudinal spaces or channels G.

1 claim—

The design for surface ornamentation of walls, &c., substantially as herein shown and described, consisting in the truncated hexagonal pyramidal elevations A, each elevation having at its summit a raised flat-surfaced hexagonal elevation, F, and interposed between said elevations A trilateral pyramidal elevations B and C, the said elevations A, B, and C being disposed in rows longitudinally the surface and separated by diagonal channels or 35 spaces D and E and longitudinal channels G.

FREDERICK MANKEY.
